SILO UNLOADER DRIVE WHEEL

Floyd E. Buschbom, Long Lake, Minn., assignor to
Van Dale Corporation, Long Lake, Minn., a corpo-
ration of Minnesota

Filed Nov. 15, 1967, Ser. No. 9,433

Term of patent 14 years

(Cl. D55—1)

FIGURE 1 is a front perspective view of a silo unloader drive wheel showing my new design;

FIGURE 2 is a front elevation view;

FIGURE 3 is a rear side elevation view; and

FIGURE 4 is a cross-section taken on line 4-4 of FIG. 3.

I claim:

The ornamental design for a silo unloader drive wheel, substantially as shown.
